GEORGE STEPHEN PROCTOR AND JOHN BARRETT PRENDERGAST, OF OTTAWA, ONTARIO,
CANADA.

SEALING-WAX MELTER.

1,129,900.

Specification of Letters Patent.

Patented Mar. 2, 1915.

Application filed May 24, 1913. Serial No. 769,598.

To all whom it may concern:

Be it known that we, GEORGE STEPHEN PROCTOR and JOHN BARRETT PRENDERGAST, both of the city of Ottawa, county of Carleton, Province of Ontario, Dominion of Canada, have invented certain new and useful Improvements in Sealing-Wax Melters; and we do hereby declare the following to be a full, clear, and exact description of the invention, such as will enable others skilled in the art to which it appertains to make and use the same.

This invention relates to improvements in sealing wax melters, and the objects of the invention are to provide a simple and effective device by which sealing wax may be melted and applied to any article without waste or danger of fire.

The invention consists essentially in the novel construction and arrangement of parts more particularly set forth in the following specification and the drawings that form part of the same.

In the drawings: Figure 1 is a sectional elevation of the device, and Fig. 2 is a general perspective view of the device. Fig. 3 is a sectional detail of the nose.

Like numerals of reference indicate corresponding parts in each figure.

Referring to the drawings: 1 is the holder or handle, which may be made of hard rubber, asbestos, fiber or the like, and which is formed with the orifice 2, adapted to receive a stick of sealing wax, and with a smaller orifice 3 adapted to receive wires 4 conveying electrical energy.

5 is a double button or other suitable form of switch, arranged and connected for making or breaking the circuit in the melting apparatus.

6 is a tube or sleeve preferably of zinc aluminum, adapted to fit into and be secured to the end 7 of holder 1.

8 is the nose or melting piece of the device, having the tapered orifice 9, across which orifice are arranged the heat conducting bars 10, said bars being secured to the nose 8, and like it, preferably of copper. 11 is a groove on the outside of said nose, 50 adapted to receive the insulation 12, and wound thereon are the coils 13 which are preferably of German silver wire of a suitable section to act as a heating agent when electrical energy is passed through them.

If found desirable insulation may be arranged between the coils of said wire.

14 is a cap or shield, which fits over the nose of the device, keeping the same in position, also protecting the heating coils 13.

It is preferable to insert a washer 15 of a material adapted to act as a non-conductor of heat between the nose 8 and the sleeve 6, also a ring 16 of the same material between the nose 8 and the cap 14.

In the operation of this device, the sealing wax bar is dropped into the orifice 2, and by using the switch 5 current is passed through the heating coils 13, which quickly heat the nose 8 and the wires 10 sufficiently to melt the end of the stick of sealing wax 70 touching the nose.

The particular purpose of the wires 10, is to provide an evenly heated flow of wax, and to disturb the wax in its downward flow, thus preventing lumpiness.

Since many changes might be made in the above construction, also many apparently different embodiments made of the invention within the scope of the claims, such constructions not departing from the spirit or scope of the invention, it is intended that all matter contained in the foregoing specification and in the drawings shall be interpreted as illustrative rather than as binding in regard to detail.

What we claim as our invention is:

1. A device of the class described comprising a holder having an orifice therethrough adapted to receive a stick of sealing wax and being provided with a second orifice extending therethrough, a sleeve adapted to engage with the lower end of the first said orifice, a nose piece having a tapered orifice therethrough, such nose piece being designed to be mounted on the end of the said holder, electric wires adapted to pass through the second said orifice, such wires being wound around the said nose piece, a switch extending through the outer periphery of the second said orifice and adapted to control the electric energy in the said coils, a shield to fit over the said nose piece, such shield being designed to engage with the outer periphery of the said holder and a washer of non-conducting material located between the said nose piece and the said shield, as and for the purpose specified.

2. A device of the class described compris-

ing a holder having an orifice therethrough, a sleeve adapted to engage with the lower end of the said orifice, a nose piece having a tapered orifice therethrough, such nose piece being designed to be mounted on the end of the said holder, a switch, heating coils wound around the said nose piece such coils being adapted to be heated by electrical energy governed by said switch, a shield adapted to fit over said nose piece, such shield being designed to engage with the outer periphery

of the said holder and bars extending diametrically across the tapered orifice in the said nose piece, as and for the purpose specified.

15

In witness whereof we have hereunto set our hands in the presence of two witnesses.

GEORGE STEPHEN PROCTOR.
JOHN BARRETT PRENDERGAST.
